(57) **CLAIM**

The ornamental design for a light-emitting necklace, as shown and described.

DESCRIPTION

FIG. 1 is a perspective view of a light-emitting necklace showing my new design;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top plan view thereof;

FIG. 7 is a bottom plan view thereof;

FIG. 8 is an enlarged cut-away perspective view of a connector portion of my new design;

FIG. 9 is an enlarged cut-away front elevational view of a connector portion thereof;

FIG. 10 is an enlarged cut-away rear elevational view of a connector portion thereof;

FIG. 11 is an enlarged cut-away top plan view of a connector portion thereof; and,

FIG. 12 is an enlarged cut-away bottom plan view of a connector portion thereof.
